DISHWASHER

Marselius T. Ashe, Garden City, N. Y.

Application June 7, 1939, Serial No. 277,815

1 Claim. (Cl. 141—9)

This invention relates to dish washers in general and more especially to dish washing machines having a standard tank and a water agitator associated therewith.

Among the objects of the present invention, it is aimed to provide an improved dish washing machine having a tank for receiving a tray or trays of dishes, cutlery and the like, and a water agitator associated with the bottom of the tank for directing the water upwardly along the sides of the tank and then inwardly on to the dishes and cutlery to be washed.

It is another object of the present invention to provide an improved dish washing machine having a tank free of any interior obstruction associated with a water agitator for directing the water upwardly along the walls of the tank and then inwardly upon the dishes and cutlery to be washed.

It is still another object of the present invention to provide an improved dish washing machine having a double walled container for receiving trays of dishes, cutlery and the like, and a water agitator associated with the lower end of the tank for directing the water up along the sides of the wall and devices associated with the agitator and walls of the tank for thereupon directing the water inwardly upon the dishes and cutlery contained in the trays.

These, and other features, capabilities and advantages of the invention will appear from the subjoined detail description of one specific embodiment thereof illustrated in the accompanying drawings in which

Figure 1 is a transverse section of a dish washing machine made according to the present invention; and

Fig. 2 is a plan of the same with parts broken away.

In the embodiment shown there is illustrated a tank 1 having an outer wall 2 consisting of an upper cylindrical portion 3, and a lower inwardly flaring stepped bottom 4. Inside of the outer wall 2 there is provided an inner wall 5 having an upper cylindrical portion 6 fitting within the cylindrical portion 3 and having an inwardly flaring bottom 7 fitting within the bottom 4 and terminating in the outwardly extending conical flange 8. The outer tank 2 is shown in the present instance as supported by the platform 9 having a cylindrical opening to receive the tank 2 and permit the outwardly extending flange 10 to rest on the upper surface of the platform 9 surrounding the tank as indicated. This flange 10 in the present instance is shown as secured

to the platform 9 by three wood screws 11, 12 and 13, preferably equally spaced from one another. In the present instance the flange is provided with a raised portion 14 having a bayonet slot 15 therein to receive the projections 16 in the annulus 17, having the inwardly extending flange 18 and the shoulder 19 above the flange 18. The flange 18 as shown, preferably has a concave face flaring downwardly and outwardly above the cylindrical chamber 20 formed between the cylindrical walls 3 and 6 of the tanks 2 and 5. The outer edge of the flange 18 as shown preferably snugly engages the inner face of the wall 3 of the outer container 2. The shoulder 19 as shown is provided to form a seat for the cover 21. The annulus 17 is thus readily removable by merely rotating the same so that its pins 16 may be moved from the diminished portions to register with the enlarged portions 20 of the bayonet slots 15 and then the annulus 17 raised relative to the tank element 2. The annulus 17 may preferably be chromium plated and conceal the flange 10 of the container 3, the outer edge of the annulus 17 resting as shown 25 on a surfacing element 22 such as linoleum, Monel metal or the like. This surfacing stock 22 as is customary with modern sink construction is generally matched with a second surfacing element 23 secured to the vertical wall 24 connected to the building uprights, such as the uprights 25. Over the front edge of the sheet 22 as shown in Fig. 2, there may be secured a metal trimming 26 composed of a chromium plated sheet metal strip or the like.

35 In the present instance, there is connected to the wall 4 of the outer tank 2, a casting 27 which performs the several functions now to be described. As an instance, it has a lower tubular extension 28 to receive the journal packing for 40 the shaft 29. In the next place it has an upwardly flaring element 30 having an outwardly stepped surface conforming with the outwardly stepped elements 31 and 32 of the wall portion 4 of the outer wall 3. In the next place it has a 45 conical seat 33 to receive the lower face of the impeller 34. Still furthermore it has extending upwardly therefrom the V-shaped baffle plates 35 which serve to change the direction of the water being agitated in a manner hereinafter 50 to be described and in addition serve to determine the space between the wall 7 of the inner tank 5 and the wall 4 of the outer tank 2. The casting 27 also has an opening 36 positioned between its tubular extension 28 and its outwardly flaring portion 30 in communication with the 55

annular recess 37 facing upwardly between the flaring portion 30 and tubular extension 28 of the casting 27. The intermediate portion 38 of the casting 27 is threaded to receive the nut 39 which is adapted to engage the lower face of a second casting element 40 which has an upper outwardly flaring face to engage the lower stepped portion 31 of the wall 4. This casting 40 also has a chambered opening 41 registering with the opening 42 in the stepped portion 31 of the wall 4 and the opening 36 in the casting 27. These registering openings 36, 42 and 41 serve as an outlet to drain the water from the tank 1. For controlling this outlet, the opening 41 is preferably provided with a tubular unit 43 connected to the valve unit 44 by the union 45 which valve 44 in turn is provided with a discharge conduit 46 and a handle 47 for controlling the same. The handle 47 in the present instance is shown as pivotally connected with the link 48 extending up to the arm 49 and pivotally connected to it as shown which arm 49 in turn is fixed to the handle 50 suitably mounted in a bearing 51 connected to the wall element 24 as shown in Fig. 2.

When the nut 39 is drawn up tightly it will appear from the foregoing that it will securely anchor the outer tank 2 between the castings 40 and 27. For connecting the inner tank 5 to the outer tank, the screws 52 may be provided having the heads 53 engaging the outer face of the stepped portion 32 of the wall 4 and extending through the flaring portion 30 of the casting 27 to and through the wall portion 7 of the inner tank 5 and provided with the wing nuts 54 on the inner face of the wall 7. These screws 52 are preferably equally spaced from one another, in the present instance each shown as extending through a V-shaped baffling unit 35, see Fig. 2.

In the present instance, there are provided six of the V-shaped baffling units 35 equally spaced from one another with their apices terminating at about the shoulder 55 of the casting 27. It will be noted that the V-shaped baffling units 35 tend to restrict the width of the flow in an outward direction as distinguished from a construction, as an instance, in which single-walled baffle plates would divide this area into six spaces. Slightly spaced from the outer ends of the wall elements of each baffle unit 35, there are formed the baffle strips 56 connected to the outer face of the inner tank 5, each strip extending for a short distance along the outer face of the wall element 7 and then up along the outer face of the wall element 6. The height of these strips 56 conforms substantially to the height of the baffle units 35 and the outer edges thereof substantially engage the inner face of the outer tank 2 so that the spaces between the strips 56 form passages for receiving the water being directed outwardly between adjacent baffling units 35. The strips of course also serve to space the inner tank 5 from the outer tank and to position the same relative to the upper baffling flange 18. The inner tank 5 preferably is provided with two lower main rows of openings 57 and 58, an upper main row of openings 59 and an intermediate row of openings 60 between the rows of openings 57 and 59. In the present instance, the rows 57 and 58 are disposed at the level above the upper edge of the tray 61, the main row of openings 59 above the upper edge of the tray 62 and the intermediate row of widely spaced apart openings 60 disposed intermediate the upper and lower edges of the tray 62. The tray 61 is intended to carry the dishes preferably set edge-wise

therein, with at least some of them extending above the upper edge of the tray 61, and the tray 62 is intended as an instance to contain cutlery and the like and possibly smaller dishes. From 5 the foregoing, as will hereinafter be described in detail, it will appear that when the impeller 34 secured to the shaft 29 is rotated, the valve 44 closed, and sufficient water has been supplied to the tank 1, that the water will be forced upwardly between the walls 3 and 6 of the tank 1, some 10 of it discharged through the openings 57, 58, 59 and 60 in streams and other portions of it deflected by the flange 18 in a sheet of water onto the contents in the trays 61 and 62. It is of course understood that according to the well 15 known practice, the water will have a predetermined temperature and be supplied with a suitable soap or scouring mixture and that the height of the water will also be determined according to 20 the velocity of the motor. In other words, the object desired or the ideal condition desired is to have a sufficient pressure maintained in the water by the impeller to force a steady sheet of water from the flange 18 and at the same time 25 a steady series of streams from the openings 57, 58, 59 and 60 onto the dishes or articles to be washed and with a sufficient force effectively to wash the same with the temperature of water and scouring mixture used.

30 The impeller 34 consists of a base 63 having a plurality of openings 64 formed in the plane annular portion 65 disposed between the upwardly flaring portion 66 and the central cap portion 67, the cap portion 67 being secured to the upper 35 end of the shaft 29 by any suitable means such as the pin 68. The openings 64 are disposed in the present instance, directly above the annular channel 37 so as to facilitate draining the water from the tank 1 after use. The upper face of the 40 cap 67 is preferably conical, the apex of which extends to a height in the present instance to the lower surface of the flange 8 to prevent the formation of a whirlpool at the center of the impeller and facilitate the centrifugal force in directing the water outwardly to and into engagement with the impeller blades 69. In the present 45 instance, see Fig. 2, there are shown six arcuate impeller blades 69 overlapping one another, terminating at their outer edges at the outer end 50 of the upper surface of the flaring portion 66 and terminating at their inner ends just outside of the flange 8. From the foregoing it will be seen that the blades 69 will receive the water from the 55 annular area 65 and then direct it between the faces of adjacent baffles 35, in turn to direct it between adjacent baffles 56 upwardly between the walls 3 and 6 of the tanks 2 and 5. The water in its upward course and due to the pressure generated is forced inwardly through the 60 openings 57, 58, 59 and 60 of the tank 5 in a plurality of streams and the surplus is thrust upwardly against the flange 18 and discharged in an annular sheet of water onto the contents within the container 5.

65 The trays 61 and 62 are preferably composed of wide wire mesh such as conventionally used in dish drying racks and the like. In the present instance, the tray 61 has two annular reenforcements 70 and 71 composed of flat stock, the 70 annulus 70 being disposed adjacent the outer upper edge of the tray 61 and the annulus 71 disposed adjacent the outer lower edge of the tray 61. In addition, the tray 61 is provided with two handles composed of flat stock, the handle 72 on the one side alone being shown 75

which extends down and which is connected to a diagonally extending bottom reenforcement 73 connected to an upright of the handle at the other end of the container not shown. The other upright of the handle 72 is connected to the diagonally extending bottom reenforcing cross-piece 74 which extends to the other upright of the other handle not shown. The tray 62 is similarly provided with two annular reenforcing rings composed of flat stock, to wit, the ring 75 adjacent the outer upper edge of the tray 62 and the ring 76 adjacent the outer lower edge of the tray 62. The tray 62 is also provided with two handles one of which 77 being shown, the upright on one side extending down to the diagonally extending reenforcement 78 which extends over to one of the uprights of the other handle not shown. The other upright of the handle 77 extends down alongside of the tray 62 and continues in the diagonally extending reenforcing cross-piece 79 which extends over to the other upright of the other handle not shown.

The ring 76 of the tray 61 conforms to the inner face of the container 5 and rests as shown on the upper end of the wall 7 where it leaves the cylindrical portion 6. The upper tray 62 will rest on the upper face of the handles 72 of the lower tray and preferably, although not necessarily, the ends of the cross-pieces 78 and 79 may rest upon the upper faces of the handles 72 as shown in Fig. 1.

Preferably the shaft 29 is provided with a packing 80 disposed between the bushings 81 and 82 with a bearing ring 83 as shown between the bushing 81 and the cap 67, and a nut 84 screw-threadedly connected to the lower end of the tubular extension 27 to press the bushing 82 upwardly and position the packing 80, bushing 81 and ring 83 up against the lower end of the cap 67. The shaft 29 as shown is fixed to the hub 85 of the pulley 86 which is connected by the belt 87 to the pulley 88 fixed to the shaft 89 of the motor 90 secured by the supporting frame 91 to the side wall 92. From the side wall there extends the bracket 93 having a journal 94 at the outer end thereof to receive the shaft 29, the lower end of which has fixed thereto a ring or collar 95 disposed along the lower outer face of the journal 94.

The outer wall of the outer container 2 in the present instance, serves as a support for the annulus 17 having a flange forming the baffle 18 and the cover seat 19 and serves also as a support for the inner wall or the inner container 5. It is of course understood that in turn the container 2 is preferably connected to a main support such as the platform or sink table 9.

While it is obvious that the dimensions of the containers 2 and 5 will vary according to the quantity of dishes to be washed, the dimensions of the impeller blades relative to the space between the containers, and that the inclination and number of baffles between the two containers may vary according to the quantity of water used, it is believed desirable to call attention to the fact that excellent results have been achieved when the machine is characterized by the following dimensions, area relations, speed of motor and the like, to wit, the diameter of the outer container eighteen inches, the altitude from the top or eye portion of the impeller 34 to the upper edge of the outer container substantially twenty inches with a flare of about thirty degrees for the lower

portion of the outer container and the space between the containers 2 and 5 substantially three-sixteenths of an inch, the space between the upper edge of the inner container 5 and the lower face of the baffle plate 18 not in excess of one inch, the number of holes 57, 58, 59 and 60 one hundred and twenty, and their diameter about one-fourth of an inch, the outer diameter of the impeller 34 six inches with the eye about four inches in diameter and the blades 69, six in number, about two and one-half inches in length and disposed at an angle of approximately forty-five degrees at their outer ends to the outer ends of the radii of the circle intersecting the outer ends of the blades 69, the water level not over five inches from the top of the eye of the impeller 34, and the revolutions per minute of the impeller 34 between eight hundred and eight hundred and fifty.

It is obvious that various changes and modifications may be made to the details of construction without departing from the general spirit of the invention as set forth in the appended claim.

I claim:

A dish washer including two nested containers, narrow baffles formed between said containers to space the same from one another and form shallow passages, each container having an upper cylindrical wall and a lower inwardly and downwardly tapering wall, the cylindrical wall of said inner container having a plurality of openings therein and the tapering wall of the inner container having a central opening at its lower end, an annular baffle spaced from the upper edge of said inner container, a bearing bracket operatively connected to the lower end of the tapering wall of the outer container, a vertically extending shaft journaled in said bracket, a driven pulley connected to the lower outer end of said shaft, a rotary agitator connected to the upper end of said shaft and having impeller blades extending beyond the outer edge of the central opening of the inner container and between the opposing faces of the tapering walls of said containers for exercising an outward pressure on the water received by said blades, the baffles between said container walls receiving the water so subjected to pressure by said blades and directing the same upwardly through said shallow passages to eject streams of water through said plurality of openings and for directing the water into engagement with said annular baffle to issue an inwardly directed stream of water into said inner container over the upper edge of the cylindrical wall of said inner container, said bearing bracket having an upwardly flaring portion disposed between said rotary agitator and the inner face of the flaring wall of said outer container and having a downwardly extending tubular extension, an outer bracket engaging the outer face of the flaring wall of said outer container and a nut screw-threadedly connected to the tubular extension of said bearing bracket and clamping said outer bracket and intervening flaring wall portion of said outer container between the flaring portion of said bearing bracket and said nut, the flaring portions of said bearing bracket and outer container and a portion of said outer bracket having registering communications, and a drain cock connected to said outer bracket in registration with the opening therein to control the drainage from said containers.

MARSELIUS T. ASHE.
